(57) **CLAIM**

The ornamental design for a punt with cork retainer for a wine bottle, as shown and described.

DESCRIPTION

FIG. 1 is a perspective view from above of the punt with cork retainer for a wine bottle;

FIG. 2 is a perspective view from below;

FIG. 3 is a front elevation view, the rear elevation view being a mirror image;

FIG. 4 is a right side elevation view, the left side elevation view being a mirror image;

FIG. 5 is a top plan view;

FIG. 6 is a bottom plan view;

FIG. 7 is a sectional view taken along line 7-7 in FIG. 6; and,

FIG. 8 is a sectional view taken along line 8-8 in FIG. 6.

In the drawings, the broken lines illustrate features and environmental subject matter that form no part of the claimed design.

1 Claim, 4 Drawing Sheets
